STABILIZATION PROCESSOR FOR PHOTOGRAPHIC FILM

Wesley Arthur Stewart, Glendale, and Peter Meyers,
Sepulveda, Calif., assignors to M. P. Goodkin Com-
pany, Irvington, N.J., a corporation of New Jersey

Filed Dec. 12, 1969, Ser. No. 20,482

Term of patent 14 years

Int. Cl. D16—06

U.S. Cl. D61—1

FIG 1

FIG 2

FIG 3

FIG. 4

FIG. 5

FIG. 6

FIG. 1 is a perspective view showing the front, top and left side of a processor embodying the ornamental design; FIG. 2 is a left-side view taken on line 2—2 of FIG. 4; FIG. 3 is a right-side view taken on line 3—3 of FIG. 4; FIG. 4 is top view of the processor; FIG. 5 is a front elevation on line 5—5 of FIG. 4; and FIG. 6 is a rear elevation on line 6—6 of FIG. 4, with a wire-frame film guide removed for clarity.

We claim:

The ornamental design for a stabilization processor for photographic film, substantially as shown.
